US00D866221S

(12) **United States Design Patent** (10) **Patent No.:** **US D866,221 S**
(45) **Date of Patent:** **** Nov. 12, 2019**

(54) **VALANCE**

(71) Applicant: **Edwin Chiquin**, Miami, FL (US)

(72) Inventor: **Edwin Chiquin**, Miami, FL (US)

(73) Assignee: **Vertilux Limited**, Miami, FL (US)

(**) Term: **15 Years**

(21) Appl. No.: **29/644,870**

(22) Filed: **Apr. 20, 2018**

(51) **LOC (12) Cl.** **06-10**

(52) **U.S. Cl.**

USPC **D6/579**

(58) **Field of Classification Search**

(57) **CLAIM**

The ornamental design for a valance, as shown and described.

DESCRIPTION

FIG. 1 is a front view for a valance illustrating my new design;

FIG. 2 is a front, right side view thereof;

FIG. 3 is a right side view thereof;

FIG. 4 is a left side view thereof;

FIG. 5 is a top view thereof;

FIG. 6 is a top, left side view thereof;

FIG. 7 is a rear view thereof;

FIG. 8 is a perspective view thereof;

FIG. 9 is a bottom view thereof; and,

FIG. 10 is a bottom, right view thereof.

1 Claim, 10 Drawing Sheets
